PROCESS OF TREATING LUBRICATING OILS
WITH SELECTIVE SOLVENTSJames M. Whiteley, Jr., Roselle, N. J., assignor to
Standard Oil Development Company, a corpo-
ration of DelawareNo Drawing. Application October 18, 1933, Serial
No. 694,039

4 Claims. (Cl. 196—13)

This invention relates to a process of treating comparatively heavy oils such as lubricating oils with selective solvents, and will be fully understood from the following description:

It is known that treatment with selective solvents such as phenol, the various cresols, furfural, beta-beta dichlorethyl ether, nitrobenzene, methyl ethyl ketone, dibutyl phthalate, aniline, etc., improves mineral oils by removal therefrom of certain undesirable constituents of unsaturated, naphthenic, or aromatic character. The present invention more specifically relates to an improved method of treating relatively heavy oils such as lubricating oils obtained from petroleum or from a primary tar or from a hydrogenated coal product, etc., with a selective solvent which is liquid or solid at ordinary room temperature and pressure. The improvement consists in carrying out the treatment of the oil with the selective solvent in the presence of an indifferent organic solvent which shows no special selectivity toward the various components of the oil if used alone and preferably is miscible in all proportions with both the oil and the selective solvent at the treating temperature. As examples of such indifferent organic solvents, we may mention aromatic hydrocarbons such as benzol, toluol, xylol, naphthalene, dimethyl naphthalene, further carbon disulfide, propyl ether, ethyl ether, etc. I have found that by carrying out the extraction with the selective solvent in the presence of an indifferent organic solvent the process is greatly improved, not only as regards selectivity, but also from the viewpoint of ease of handling, working temperature, solvent recovery, and lack of emulsification trouble.

The case of the extraction of Pennsylvania lubricating oils with phenol will illustrate in more detail the advantages which are obtained by the present process. When it is desired to treat Pennsylvania lubricating stocks with phenol it is found that these stocks are not miscible with the phenol until temperatures above 100° C. are reached. Benzol is miscible with both the oil and the phenol in all proportions. Therefore, it distributes between the two layers when added to the mixture. It lowers the melting point of the phenol to 19° C. so that working temperatures between 19° C. and 44° C., for example, can be used as well as temperatures above 44° C. The benzol lowers the temperature of operation so that Pennsylvania lubricating stocks can be extracted at 25° C. with ease. If it is desired to lower the extraction temperature still further, a small amount, say 3%, of naphtha may be added. The amount of benzol in the blend determines the extraction temperature. The benzol does not change the selective power of the phenol. The same yields and oils of the same quality are produced with the same amount of phenol. The

benzol is actually an inert diluent. The solvent recovery is not difficult. The benzol and phenol boil far apart from each other and from the lubricating oil stock so that they can be separated by simple distillation from both the solvent layer and the oil layer. Neither solvent is decomposed by heat, nor has any effect on the oil treated.

The case of heavy tarry stocks serves to illustrate certain other advantages of the present invention. Such stocks when treated with a selective solvent form bad emulsions. When, however, the extraction with the selective solvent is carried out in the presence of an indifferent organic solvent, the latter dissolves in the oil layer and lowers its viscosity so that no emulsion trouble is encountered.

The inert solvent, to give the best results, should be structurally "similar" to the selective solvent, the main difference being that the selective solvent contains oxygen while the inert solvent does not. For instance, benzol is similar to phenol in that the phenol is made selective by the substitution of an OH group in benzol. The inert solvent ethylene dichloride is similar to the selective solvent beta-beta dichlorethyl ether.

The treating is carried out in the usual way. The oil is agitated with the mixture of inert and selective solvent and then allowed to settle until it separates into a solvent layer and an oil layer. The solvent layer consists of selective and inert solvent and also contains the extract which has been removed from the oil. The oil layer contains the raffinate together with a certain amount of dissolved inert and selective solvents. The two layers are separated from each other and the solvents are then removed from both layers by distillation or by other means known in the art. The treating may be carried out either in a batch process or in a continuous process which may be countercurrent. Very often several batch treatments are used in succession according to the countercurrent principle.

The inert solvent may be admixed with the solvent or part of the inert solvent may be added to the oil. The latter operation is especially advantageous when the treating is carried out in a continuous countercurrent operation. This has two advantages: (1) The oil feed is made less viscous and better extraction is obtained, and (2) the equilibrium condition at the feed inlet of the system is attained much more quickly since the tendency of the entering oil to dissolve more of the inert solvent than of the selective solvent is thereby satisfied.

The present invention results in maximum benefit when used with solvents such as phenol, furfural, dichlorethyl ether, nitrobenzene, methyl cellosolve, etc. which have a high miscibility temperature with the oil. This miscibility temperature is lowered due to the presence of

the inert solvent and consequently the extraction may be carried out at or around room temperatures.

The following examples will illustrate the invention.

An oil of the following inspections had the following miscibility temperatures with phenol-benzol mixtures:—

10	Saybolt vis/100° F.	636
	Saybolt vis/210° F.	73
	Gravity °A. P. I.	28.4
	Viscosity index	103

15	Oil	Phenol	Benzol	Miscibility temperature
	1	1	0	109° C.
	1	2	1	41° C.
	2			69° C.

20

This oil was extracted with a solvent containing two parts phenol, and one part benzol at 27° C. to a countercurrent column. Five hundred parts of oil was extracted with 1000 parts of total solvent. The raffinate was obtained with 78% yield and had the following characteristics:

30	Saybolt vis/100° F.	492
	Saybolt vis/210° F.	67.2
	Gravity °A. P. I.	30.8
	Viscosity index	110

The extracted material, 22%, had a viscosity of 126 at 210° F. and a viscosity index of 58.

As a second example, Pennsylvania bottoms oil dewaxed had the following viscosity characteristics and miscibility characteristics:

40	Vis/100° F.	4137
	Vis/210° F.	237
	Viscosity index	105

45	Oil	Phenol	Benzol	Miscibility temperature
	1	1	0	141° C.
	1	1	1	68° C.

When extracting this heavy oil, an attempt was made to add an equal volume of benzol to the feed oil and extract with a solvent containing 3 parts of benzol to 4 parts of phenol at 25° C. in a countercurrent column. The feed oil dissolved in the solvent completely so that another run had to be made using only 10% benzol in the feed oil. Equilibrium was easily set up. Three volumes of oil was extracted with 10 volumes of total solvent containing 6 volumes of phenol and 4 volumes of benzol.

The raffinate and extract obtained were as follows:

	Raffinate	Extract
65	Yield	72%
	Gravity °A. P. I.	28.2
	Saybolt vis/100° F.	19.9
	Saybolt vis/210° F.	7200
	Viscosity index	246
		79
		115

Other experiments showed that the selectivity of the phenol is not adversely affected.

The present invention may be modified in various ways. Thus, for example, a mixture of several inert solvents may be added to the selective solvent in order to obtain the desired re-

sult. Other modifications will be apparent to those skilled in the art.

The invention is, therefore, not to be limited by the data given in the examples for illustration but only by the following claims in which it is my intention to claim all novelty inherent in the process.

What I claim is:

1. In a solvent extraction of lubricating oil wherein a selective solvent, capable of selectively dissolving non-paraffinic constituents of said oil, is passed into the upper portion of an extracting zone and the oil to be treated is passed into a lower portion of said extracting zone and the undissolved constituents of said oil pass in countercurrent contact with said selective solvent and are withdrawn from the upper end of said extraction zone whereas the selective solvent and oil dissolved therein is withdrawn from the bottom of said extracting zone; the improvement which comprises carrying out the extraction process with a selective solvent having a high miscibility temperature in the presence of a non-selective diluent capable of reducing the miscibility temperature of said oil and solvent, adding a portion of said non-selective diluent to the fresh oil to be treated in an amount less than the amount of oil being treated and adding additional non-selective diluent to the selective solvent introduced into said extraction zones. 30

2. In the solvent extraction of lubricating oil wherein a selective solvent, capable of selectively dissolving non-paraffinic constituents of said oil, is passed into the upper portion of an extracting zone and the oil to be treated is passed into a lower portion of said extracting zone and the undissolved constituents of said oil pass in countercurrent contact with said selective solvent and are withdrawn from the upper end of said extraction zone whereas the selective solvent and oil dissolved therein is withdrawn from the bottom of said extracting zone; the improvement which comprises carrying out the extraction process with phenol as the selective solvent in the presence of a non-selective diluent capable of reducing the miscibility temperature of said oil and solvent, adding a portion of said non-selective diluent to the fresh oil to be treated in an amount less than the amount of oil being treated and adding additional non-selective diluent to the selective solvent introduced into said extraction zones. 50

3. In the solvent extraction of lubricating oil wherein a selective solvent, capable of selectively dissolving non-paraffinic constituents of said oil, is passed into the upper portion of an extracting zone and the oil to be treated is passed into a lower portion of said extracting zone and the undissolved constituents of said oil pass in countercurrent contact with said selective solvent and are withdrawn from the upper end of said extraction zone whereas the selective solvent and oil dissolved therein is withdrawn from the bottom of said extracting zone; the improvement which comprises employing phenol as the selective solvent, adding benzene to the fresh oil to be treated in an amount less than the volume of oil being treated and introducing additional benzene into said extracting zone. 65

4. In the solvent extraction of lubricating oil wherein a selective solvent, capable of selectively dissolving non-paraffinic constituents of said oil, is passed into the upper portion of an extracting zone and the oil to be treated is passed into a lower portion of said extracting zone and the undissolved constituents of said oil pass in counter- 75

current contact with said selective solvent and are withdrawn from the upper end of said extraction zone whereas the selective solvent and oil dissolved therein is withdrawn from the bottom of said extracting zone; the improvement which comprises employing phenol as the selective sol-

vent, adding benzene to the fresh oil to be treated in an amount equal to about 10 percent of the volume of oil being treated and introducing additional benzene to said extracting zone in amount not in excess of the total phenol employed. 5

JAMES M. WHITELEY, JR.
